UNITED STATES PATENT OFFICE.

JAMES T. OWENS, OF WASHINGTON, DISTRICT OF COLUMBIA.

SMOKE-BELL SUPPORT.

974,702.

Specification of Letters Patent.

Patented Nov. 1, 1910.

Application filed June 10, 1910. Serial No. 566,261.

To all whom it may concern:

Be it known that I, JAMES T. OWENS, a citizen of the United States, residing at Washington, in the District of Columbia,

5 have invented certain new and useful Improvements in Smoke-Bell Supports, of which the following is a specification.

My invention relates to devices to be suspended from hangers and especially to smoke 10 bells for lamps, especially for gas lights, and means for suspending them.

It is very often desirable to suspend smoke 15 bells over lights without marring the ceiling by the securing therein of hooks, the ceiling being very often punctured, disfigured, or broken down by unsuccessful efforts to find the ceiling joists in fixing hooks in position from which to suspend the bells. Very often when the ceiling joist is located, it is 20 not in proper position above the light. On account of such danger of mutilation or destruction, and wrong location of ceiling joists, the bells are very often dispensed with, thus permitting the ceiling to become 25 disfigured by the smoke as the lesser evil.

The object of my invention is to provide 30 economically constructed and easily operated means whereby smoke bells and any other article near an upright bar, pipe or support, may be readily suspended in proper position and taken down when desired, without in any manner marring or disfiguring the ceiling or wall, and with this object in view my invention consists in the improved 35 support, the construction, arrangement and combination of the parts of which will be hereinafter fully described, the particular points of novelty therein being set up in the appended claims.

40 I have illustrated an embodiment of my invention in the accompanying drawing, in which—

Figure 1 represents, partly in vertical section and partly in elevation, a two light 45 chandelier with my invention in place thereon. Fig. 2 represents in perspective the simplest form of my support. Fig. 3 represents a vertical sectional view showing a support for two lateral arms, the clasping ring being 50 shown in open position in dotted lines. Fig. 4 represents a view, similar to Fig. 3, showing a support for three lateral arms. Fig. 5 represents, in perspective, a support for four lateral arms. Fig. 6 represents, in perspective, a portion of the upper member of 55 the cover, showing the inside thereof, with

the securing means, and Fig. 7 represents, in perspective, a modification of the two arm support, with extensible arms in position therein.

60

Like reference characters mark the same parts wherever they appear in the several figures of the drawing.

Referring specifically to the drawing, 10 indicates the vertical pipe of a gas light 65 chandelier which depends from the ceiling and carries at its lower end any desired number of lateral pipes 11, each terminating in a burner, as at 12.

In Fig. 1, I have shown the vertical pipe 70 10 clasped by a wire loop 13, the central portion of which, on one side of the pipe, is formed into a vertical coil, as at 14, the wire of the loop being bent downward from the top of the coil, as at 15, and upward 75 from the bottom of the coil, as at 16, to the plane of the loop at the mid-height of the coil. At the opposite side of the loop the ends of the wire are bent to form two smaller coils, as at 17 and 18, one end of the 80 wire being bent upward from the plane of the loop to form the coil 17 and the other end downward from that plane to form the coil 18.

The wire of which the loop is formed is 85 elastic and the two ends are normally separated, holding the loop open on that side so that it may be slipped laterally upon the pipe 10 after which the two ends are brought together causing the loop to tightly clasp 90 pipe 10 and bringing the small coils 17 and 18 into line with each other, to form substantially a single coil, into which the vertically depending hook end 19 of a lateral arm 20 may be inserted, thus not only holding 95 the loop tightly closed, but firmly supporting the arm 20 in position to support a smoke-bell, as at 21, over one of the burners. The end 22 of another lateral arm 23 may be inserted into the coil 12 to hold the 100 arm in position to support another smoke-bell over another burner. The loop may be formed without the central coil, as shown at 130 in Fig. 2, for use where there is only one burner, the end coils 17 and 18 being of 105 the same construction and operating in the same manner as described with reference to Fig. 1.

In Fig. 3, I have shown in section the loop 13 clasped on pipe 10 with the other parts in full lines in the same positions as in Fig. 1, and in dotted lines I have shown

the loop open in position to be slipped upon and closed around the pipe 10 by bringing coils 17 and 18 into line with each other to receive the hook end of the lateral arm 20 5 which, with arm 22, is shown partly broken away.

In Fig. 4, I have shown how my invention may be modified to support three lateral arms, there being formed by bending 10 the wire of the loop intermediate its ends, two coils 140, each a counterpart of coil 14, in Figs. 1 and 3, the end coils 17 and 18 being the same in construction and operation 15 as in Figs. 1, 2 and 3, and being shown separated, as in Fig. 3, in dotted lines.

In Fig. 5, I have shown in perspective, a modification for supporting four lateral arms, three coils 141, similar to coil 14 in Figs. 1 and 3, and to coils 140 in Fig. 4, being formed of the wire of the loop intermediate its ends, which ends are bent to form coils 17 and 18 as in the preceding figures, the coils 141 each receiving the hook end 22 of a lateral arm 23, and the two coils 25 17 and 18, in line with each other, receiving the hook end 19 of arm 20, as in the other forms described.

In Fig. 1, I have shown a cover for inclosing and protecting my improved support when in position on the pipe 10, said cover consisting of an inverted cone 24 above, and an upright cone 25 below the support, the one fitting upon the other as a lid fits on a box, and there being formed in their 30 meeting edges notches 26 which may be made to register with each other so that the lateral arms may project therethrough. Each of these conical members is made preferably of a single piece of sheet metal, the 35 edges of which may be separated far enough apart to slip the member on the pipe, and when in position these edges are brought together and secured by suitable hooks 27 on one member engaging notches 28 in the edge 40 of the other member, there being a series of such notches so that the members may be adjusted to fit on pipes 10 of different diameters.

In some instances it may be desirable to 50 use a separate fastener as at 29 in Fig. 7, to secure the upward and downward bends of the loop wire to the intermediate coils in order to increase the rigidity of the structure. In Fig. 7, I have also shown modified 55 forms of lateral arms, each being composed of two members 190 and 200, which are secured together in a manner to permit of longitudinal adjustment to lengthen or shorten the arms, in this instance the member 190 passing through a loop 191 on member 200, and the member 200 through a loop 201 on the member 190.

The economy of construction and utility 60 of my invention will be obvious and the scope thereof will obviously include many

variations in form of the component parts described, as well as in their relations to each other.

Having described my invention, what I claim as new, and desire to secure by Letters 70 Patent, is—

1. A device of the character described comprising a wire loop having each end formed into a coil, the axis of which is at a right angle to the plane in which the loop 75 is bent, the two coils extending in opposite directions from the plane of the loop and being adapted to be brought into position with their axes in the same line to receive and support the vertical end of a bracket 80 which also serves as a lock for the loop.

2. A device of the character described comprising a wire loop having each end formed into a coil, the axis of which is at a right angle to the plane in which the loop 85 is bent, and the wire of the loop at a point intermediate its ends being formed into a coil also at a right angle to the plane of the loop, the two end coils extending in opposite 90 directions from the plane of the loop and being adapted to be brought into position with their axes in the same line to receive and support the vertical end of a bracket 95 which also serves as a lock for the loop.

3. A device of the character described 95 comprising a wire loop having each end formed into a coil, the axis of which is at a right angle to the plane in which the loop is bent, and the wire of the loop at a point intermediate its ends being formed into a 100 coil also at a right angle to the plane of the loop, the intermediate coil having its mid-length in the plane of the loop, and the two end coils being adapted to be brought into position with their axes in the same line to 105 receive and support the vertical end of a bracket which also serves as a lock for the loop.

4. A device of the character described comprising a wire loop having each end 110 formed into a coil, the axis of which is at a right angle to the plane in which the loop is bent, and the wire of the loop at a point intermediate its ends being formed into a 115 coil also at a right angle to the plane of the loop, the intermediate coil having its mid-length in the plane of the loop, the two end coils extending in opposite directions from the plane of the loop and being adapted to be brought into position with their axes in 120 the same line to receive a wire.

5. An article of the character described, comprising a coil of wire having its ends bent outside of and substantially parallel with the axis of the coil to the midlength 125 of the coil, extended thence in a single plane lying at a right angle to the axis of the coil, in opposite directions, into the form of a loop, and bent at each end to form a coil with its axis parallel with the first named 130

coil, the axes of the end coils being adapted to be brought into a line with each other to receive and support the vertical end of a bracket which also serves as a lock for the 5 coil.

6. An article of the character described, comprising an upright, a wire loop encircling it, wire hangers, extending laterally from the loop, and funnel shaped covers on 10 the uprights above and below the loop having openings at their meeting edges through which the wire hangers extend and serve to support the funnels in position on the upright.

15 7. An article of the character described, comprising an upright, an inverted funnel shaped cover on the upright, provided with notches in its lower edge, an upright funnel

shaped cover on the upright below the inverted funnel having notches in its upper 20 edge to register with the notches in the edge of the inverted funnel, the two funnels being open and made of elastic material, means for securing the open edges of each funnel together to close them around the upright, 25 laterally extending hangers secured to the upright and projecting through the registering notches in the edges of the two funnels, and supporting the funnels in position on the upright.

In testimony whereof I affix my signature in presence of two witnesses.
